(57) **CLAIM**

The ornamental design for a sample receiving device as shown and described.

DESCRIPTION

FIG. 1 is an isometric view from the front, top, right of the sample receiving device.

FIG. 2 is an isometric view from the back, top, right of the sample receiving device.

FIG. 3 is an isometric view from the front, bottom, right of the sample receiving device.

FIG. 4 is an isometric view from the back, bottom, right of the sample receiving device.

FIG. 5 is a plan view of the top of the sample receiving device.

FIG. 6 is an elevation view of the back of the sample receiving device.

FIG. 7 is an elevation view of the right of the sample receiving device.

FIG. 8 is an elevation view of the front of the sample receiving device, wherein the portions indicated in broken lines form no part of the claimed design.

FIG. 9 is an elevation view of the left of the sample receiving device; and,

FIG. 10 is a plan view of the bottom of the sample receiving device, wherein the portions indicated in broken lines form no part of the claimed design.

The broken lines depict environment that forms no part of the claimed design.

1 Claim, 4 Drawing Sheets
